UNITED STATES PATENT OFFICE.

STANLEY E. BOYNTON, OF ROCHESTER, NEW YORK, ASSIGNOR TO THE CRAWFORD, McGREGOR AND CANBY COMPANY, OF DAYTON, OHIO, A CORPORATION OF OHIO.

SHAPING MACHINE FOR IRREGULAR FORMS.

Application filed November 17, 1921. Serial No. 515,999

The present invention relates to machines for shaping irregular forms, such as shoe lasts, golf clubs or the like, an object of this invention being to provide a machine which 5 has a roughing and a finishing tool, these tools being relatively movable so that the roughening work will at no time be imposed upon the finishing tool, as is the case, when the finishing tool maintains a fixed relation to the 10 roughing tool to operate it at a point nearer the axis of turning of the block than the roughing tool.

To these and other ends, the invention consists of certain parts and combinations of 15 parts all of which will be hereinafter described, the novel features being pointed out in the appended claims.

In the drawings:

Fig. 1 is an end view of a shaping machine 20 constructed in accordance with this invention, parts being broken away;

Fig. 2 is a front view of the machine with parts removed;

Fig. 3 is a plan view with parts removed;

Fig. 4 is a detail view showing the roughing and finishing tracers and a portion of the connections of the roughing tracer with the roughing tool;

Fig. 5 is a detail view showing in elevation 30 the roughing tracer and the rough width grading mechanism;

Fig. 6 is another view in elevation of the roughing tracer;

Fig. 7 is a detail view showing the manner 35 in which the roughing tool moves away from the axis of rotation of the block when operating to produce a high spot on the block;

Fig. 8 is a detail view showing the manner 40 in which the roughing tool moves relatively to the finishing tool nearer to the axis of rotation of the block in shaping a low spot on the block.

There is herein shown one form of shaping machine in which the present invention has 45 been embodied, but it will be distinctly understood that the invention is not limited to this type of shaping machine, as the feature of the invention of producing a relative movement between the finishing and the roughing tool 50 may be embodied in shaping machines of various other types.

In the illustrated embodiment, 1 indicates the lower portion of the main frame and 2 the upper portion of the main frame. The 55 work block and model are supported upon a

swinging frame, embodying side arms 3, journaled on shafts 4 on the upper portion of the main frame and depending from said shafts, these side arms being connected by two guide bars 5 and 6, the upper guide bar 5 having brace bars 7 secured thereto at 8 and to the side bars 3 at 9.

The block or work piece 10 is supported from the swinging frame by a block tail center 11 and a block driving dog 12, whereas 60 the model is supported from the swinging frame by a model tail center 13 and a model driving dog 14, the axes of turning of all these four parts being alined. The tail center 11 is adjustably mounted in a tail stock 65 15 in which it is adjusted by rotation of the usual crank handle, as is common in lathe construction. The block driving dog is, in this embodiment, mounted to turn in bearings 16,

which are provided on two frame pieces 17, 70 bolted at their upper and lower ends to the guide bars 5 and 6. A pinion 18 is provided on the shaft of the block driving dog 12 between the bearings 16, in order to permit the driving dog to be driven in a manner hereinafter 75 more particularly pointed out. The model tail center 13 is mounted in a bearing on a slide 19 which is guided on guide bars 5 and 6, whereas the driving dog 14 for the model

is mounted on a shaft 21 which has bearings 80 at 20 and 22 in frame pieces bolted to the guide bars 5 and 6. A gear wheel 23 between the bearings 20 and 22 on the shaft 21 meshes with a pinion 24 on a shaft 25, which has bearing 85 on one of the frame pieces 17 and on the frame piece which supports the bearing 20.

At its end opposite the end on which the pinion 24 is provided, the shaft 25 has a pinion 26 which meshes with the gear 18. It 90 is apparent that this arrangement provides a driving connection between the shaft 21 of the driving dog for the model and the shaft of the driving dog for the block, so that these two parts will turn together about the same axis and at the same speed. A pulley 27 on the shaft 21 connects by a belt 28 with a pulley 29 on one of the shafts 4, this shaft also having a pulley 30 thereon which connects with the pulley 31 on the shaft 32 journaled

at the rear of the frame 2 and driven in any 100 suitable manner, so that motion may be transmitted to the model and the block for any position of adjustment of the swinging frame on which these parts are mounted.

For cooperation with the model two tracers 110

33 and 34 may be provided, the former being what is termed a "finishing tracer" and the latter being what is termed a "roughing tracer". For cooperation with the block, two tools in the form of cutters 35 and 36 are provided, the former being what is termed a "finishing tool", and the latter being what is termed a "roughing tool".

The finishing tool or cutter 35 is, in this instance, in the form of a plurality of cutting blades mounted to turn about an axis which is at an oblique angle to the axis of turning of the block. In this instance, the finishing cutter is mounted on the shaft 37 of an electric motor 38, which is in turn mounted on a carriage 39 guided on the top of the frame part 1 on guides 40 to move parallel to the axis of turning of the block.

The carriage 39 may be moved in any suitable manner but, in this instance, it is provided with a rack 67 on its under side with which a gear wheel 68 meshes. This gear wheel in turn is driven by a worm wheel 69 on a shaft 70 on which the gear wheel 68 is mounted. A worm 71 on a shaft 72 meshes with the worm wheel 69 and is driven through a pulley 73.

The finishing tracer 33 controls the relative positions of the block and the finishing cutter and, in this instance, is so connected to the finishing cutter that the relative adjustment in their movements may be obtained for length grading and width grading. The width grading may be obtained by mounting the finishing tracer 33 upon a width grading slide 41, the latter being supported by dove tail guides on a guide way 42, which is rigidly mounted on a tracer carriage 43, the latter being shiftable horizontally on the top 40 of the frame part 1 on guides 44 formed on top of the main frame 1. The finishing tracer 33 turns about an axis at an acute angle to the axis of turning of the model. The slide 41 moves horizontally at right angles to the axis of turning of the model and carries a dovetailed slidable fulcrum piece 45 which is adjustable vertically relatively to the slide through a screw 46, having a pinion 47 meshing with a gear 48 on a shaft 49, which is turned by a crank 50. This fulcrum piece 45 in turn cooperates with a swinging member or fan board 51 which is pivoted at 52 on the upper frame part 2.

A spring, not shown, may be used to constantly hold the fan board in contact with the adjustable fulcrum. A link 53 pivotally connects to the fan board at 54 and also pivotally connects with the swinging frame at 55. The swinging frame is also acted upon by a counterweight 56 on an arm 57 which extends from a rock shaft 58, the latter being provided at opposite ends with arms 59, and links 60 connect these with the arms 3 at 61.

From the foregoing, it is apparent that the transverse movement of the block 10 is

controlled through the cooperation between the tracer 33 and the model supported on the tail center 13 and the driving dog 14. During the cooperation between the tracer 33 and the model these two parts partake of a conjoint movement which will impart to the block 10 the desired movement. The amount of this conjoint movement of the tracer 33 and the model is determined by the position of the fulcrum piece 45 on the fan board 51. If the fulcrum piece is opposite the pivot 52, then the size of the last cut, as to width, will be equal to the width of the model. If the fulcrum piece 45 is situated above the pivot 52, then the size of the last, as to width, will be greater than the size of the model. If the fulcrum piece 45 is situated below the pivot 52 then the size of the last, as to width, will be less than the model. The mechanism for connecting the finishing tracer with the model swinging frame is termed in the art "width grading mechanism" and will be herein called "the finishing width grading mechanism".

The machine may also be provided with what is known as a length grading mechanism. This comprises, in this instance, a lever 62 pivotally mounted as usual on an adjustable fulcrum block (not shown) on a fixed part and also pivotally connected at 62^a with the tracer carriage 43. This length grading lever 62 is, through an adjustable link 63, pivotally connected at 64 to the cutter carriage 39. The link 63 is also pivoted at 65 to a block 66, which is adjustable on the grading lever 62 toward and from the pivot of the latter for the purpose of obtaining length grading for the finishing cutter. It is apparent that, if the pivot 65 be shifted to the position opposite the pivot 62^a, the movements of the carriages 39 and 43 will be equal. If the pivot 65 be positioned above the pivot 62^a, then the difference in movement between the carriages will be such as to increase the length of the finished last over that of the model. Whereas, if the pivot 65 will be below the pivot 62^a then movements of the carriages 39 and 43 will be such as to decrease the length of the finished last with reference to the model. This length grading mechanism will be known, in this instance, as the finishing length grading mechanism.

The roughing tool or cutter 36 is adapted to operate on the block simultaneously with the finishing cutter 35, and to this end, may have a plurality of cutting blades 36^a mounted upon a hollow head which permits the cutter blades of the finishing cutter to operate therein in the manner shown in Figs. 3 and 8. The axis of rotation of this roughing cutter is at an acute angle to the axis of rotation of the block and with this end in view the roughing cutter is mounted upon a shaft of an electric motor 74, which is ar-

ranged upon a roughing cutter carriage 75 guided on guides 76 formed on the finishing cutter carriage 39, the line of movement of said roughing cutter carriage being at an acute angle to the axis of rotation of the block and also being at an angle to the axis of rotation of the roughing cutter 36. A spring 75^a acts on the roughing cutter carriage 75 to hold the roughing cutter toward the work piece.

A rough width grading mechanism is interposed between the roughing tracer 34 and the roughing cutter carriage 75. In this instance, it is preferred to make the roughing tracer in the form of a segment of an annulus, the plane of said segment being arranged substantially parallel with the plane of rotation of the roughing cutter, the segment being curved transversely to conform to the outermost peripheries of the cutter blades 36^a. The roughing tracer is mounted on a slide 77 which is in turn mounted to move on a slide 78, the two slides being movable in parallel lines and horizontally. The slide 78 in turn is guided on a standard 79 which is supported on the tracer carriage 43. The line of movement of the two slides 77 and 78 is parallel with the line of movement of the carriage 75 on which the roughing cutter 36 is mounted. Through a pin 80, projected from the top thereof, the slide 78 may be connected with the roughing cutter carriage 75, the latter to this end having an arm 81 extending laterally therefrom and provided with a slot 82 in which the pin 80 operates, this slot being parallel with the line of movement of the tracer carriage. Connection between the slide 77 and the slide 78 may be effected through an adjustable link 83, pivoted at 84 to the slide 77 and at 85 to a block 86 which is adjustable on a rough width grading arm 87, the latter being loosely pivoted at 88 to the tracer carriage 43 and also at 89 to the roughing tracer slide 78. A graduated scale may be provided on the rough width grading arm 87 for determining the position of the adjustable block 86. When the pivot 85 is in line with the pivot 89, the slides 77 and 78 move at the same rate of speed and, as a consequence, the roughing cutter and the roughing tracer will move together at the same rate of speed toward and from the axis of rotation of the model and the block. When the pivot 85 is above the pivot 89, the roughing tracer 34 will cause the roughing cutter 36 to produce a rough width in the block which is greater than that of the model, whereas when the pivot 85 is below the pivot 89 the roughing tracer will cause the roughing cutter to produce a rough width in the block which is less than the width in the model.

The operation of the invention will be understood from the foregoing description, but it may be summarized as follows: The model

being placed in a position between the driving dog 14 and the tail center 13, and the block 10 being placed in position between the driving dog 12 and the tail center 11, with the two cutters and the two tracers cooperating respectively with the block and the model at one end of each of them, the machine is started in operation. The roughing tracer and the roughing cutter first engage respectively the model and the block, the roughing cutter 75 preparing the block in a rough way for operation on by the finishing cutter which follows closely the operation of the roughing cutter. As the two cutters advance in the direction of the block, they move relatively to each other, the roughing cutter nearer to the axis of rotation of the block when a depression is to be formed, as in Fig. 8, and the finishing cutter nearer to the axis of rotation of the block when a high point is to be formed on the block.

The positions of the roughing and finishing cutters are controlled respectively by the roughing and the finishing tracer. Owing to the fact, that the roughing cutter carriage connects with the roughing tracer through a rough width grading mechanism, it is possible to cause the roughing cutter to produce a rough cut of the block which will correspond to different widths of lasts. The length grading mechanism for the finishing cutter also acts as a length grading mechanism for the roughing cutter, due to the fact that both cutters are mounted on one carriage 100 while both tracers are mounted on another carriage.

The tracer which controls the roughing tool or cutter is slightly larger in diameter than the roughing cutter or tool so as to leave a surplus of material for the finishing tool 105 or cutter to remove and to make it easier to set the centers of the tracer wheels and tools or cutters. It has been found in practice that the larger the amount of stock removed by the roughing tool, the more exact result 110 is obtained by the pattern and this machine permits the work of the finishing tool to be reduced to a minimum, so that more accurate work is obtained. Furthermore, a smaller amount of power is required to operate the 115 finishing cutter.

While the invention has been herein described in connection with a turning machine, it is apparent that it is capable of being embodied in any shaping machine where the 120 shaping action of two tools, cutters or otherwise, on a work piece is controlled from a model.

What I claim as my invention and desire to secure by Letters Patent is:—

1. A shaping machine having two relatively adjustable tools, one designed for rough work and the other designed for finishing work on the portions of the work piece operated upon by the roughing tool, and means 130

- controlled from a model for controlling the relative adjustment between the tools and also between a work piece and the tools.
2. A shaping machine comprising a work piece supporting means, a finishing and a roughing tool movable relatively to the work piece supporting means, model supporting means, and means for controlling the relative positions between the work piece and the two tools from a model on the model supporting means, said controlling means having provision for effecting a relative movement between the two tools, so that the finishing tool cannot hold the roughing tool out of engagement with the work piece.
3. A shaping machine comprising means for rotating a model about a suitable axis, means for rotating a work piece about an axis common to the axis of turning of the model supporting means, said work piece turning means and model turning means being mounted for movement together transversely of said axis of rotation, a finishing and a roughing tool movable together in the direction of the axis of rotation of the work piece and the model and having a relative movement transversely of the axis of rotation of the work piece and the model, and two tracers co-operating with the model, one controlling the relative positions between the work piece and the finishing tool, and the other controlling the relative positions between the work piece and the roughing tool.
4. A shaping machine comprising a work piece supporting means, model supporting means, a roughing tool for operating on the work piece, a finishing tool for operating on the work piece, and two tracers cooperating with the model on the model supporting means, one of said tracers controlling the relative positions between the work piece and the roughing tool and the other of said tracers controlling the relative positions between the work piece and the finishing tool.
5. A shaping machine comprising a means for turning the work about a suitable axis, means for turning the model about the same axis, a tool carriage movable longitudinally of the axis, a finishing and a roughing tool mounted on said carriage and having relative movement on the carriage transversely of said axis, a tracer carriage, a finishing and a roughing tracer relatively mounted on the carriage, the finishing tracer controlling the relative positions between the work piece and the finishing tool and the roughing tracer controlling the positions between the work piece and the roughing tool, and a length grading mechanism connecting the tool carriage with the tracer carriage.
6. A shaping machine comprising means for turning a work piece about a suitable axis, means for turning the model about the same axis, a tool carriage movable longitudinally of said axis, a finishing tool and a roughing
- tool mounted on the carriage and relatively movable transversely of said axis, a tracer carriage movable in the direction of the axis of rotation of the work piece and model, a finishing tracer and a roughing tracer mounted on the tracer carriage, a length grading mechanism connecting the tool and the tracer carriage, width grading mechanism for controlling the relative positions between the finishing tool and the work piece, and rough width grading mechanism controlled by the roughing tracer for controlling the relative positions between the roughing tool and the work piece.
7. A shaping machine comprising a work supporting means for rotating a work piece about a suitable axis, means for rotating a model about the same axis, a roughing and a finishing tool movable relatively transversely of said axis, a roughing and a finishing tracer movable relatively transversely of said axis, a common length grading mechanism connecting the tools with the tracers, a width grading mechanism controlling the relative positions between a work piece and the finishing tool, and a rough width grading mechanism controlling the relative positions between the work piece and the roughing tool.
8. A shaping machine comprising a swing frame, means for rotating a work piece on said frame, means for rotatably supporting the model on said frame to rotate about an axis in common with that of the work piece, a tool carriage movable longitudinally of the axis of rotation of the work piece and the model, a finishing tool and a roughing tool mounted on the carriage, the roughing tool being movable on the carriage relatively to the finishing tool transversely of the axis of rotation of the work piece, a tracer carriage movable longitudinally of the axis of rotation of the model, a finishing tracer and a roughing tracer mounted on the tracer carriage movable relatively one to the other transversely of the axis of rotation of the model, a length grading mechanism connecting the tool and the tracer carriage, connecting means between the finishing tracer and the swing frame for effecting a relative movement between the work and the finishing tool, and connecting means between the roughing tracer and the roughing tool for effecting a movement of the roughing tool relatively to the finishing tool.
9. A shaping machine comprising means for rotating a work piece about a suitable axis, means for rotating a model about the same axis, a movable frame on which said work piece turning means and model turning means are mounted, a tool carriage movable longitudinally of the axis of rotation of the model and the work piece, a finishing tool mounted to turn on the carriage about an axis at an angle other than a right angle to the axis of rotation of the model, a rough-

- ing tool mounted to turn about an axis other than at a right angle to the axis of rotation of the work piece and having a hollow portion in which a portion of the finishing tool 5 operates, a carriage on which said roughing tool is mounted to rotate, said carriage being movable on the tool carriage at an angle other than a right angle to the axis of rotation of the work piece, a tracer carriage movable in the direction of the axis of rotation of the model, a rough width grading mechanism 10 connecting the roughing tracer with the carriage of the roughing tool, a finishing tracer movable on the tracer carriage transversely of the axis of rotation of the model, width grading mechanism connecting said tracer 15 with the frame on which the model and the work piece are supported, and a length grading mechanism connecting the tracer carriage with the tool carriage.
- 25 10. A shaping machine comprising means for turning the work about a suitable axis means for turning a model about the same axis, a movable frame on which said work piece turning means and model turning 30 means are mounted, a tool carriage, a tracer carriage, length grading means connecting the tool carriage with the tracer carriage, means for moving said carriages in the direction of the axis of rotation of the work piece 35 and the model, two relatively movable tools mounted on the tool carriage, one designed for rough work and the other designed for finishing work upon those portions of the work piece operated upon by the roughing 40 tool, two relatively movable tracers mounted on the tracer carriage, width grading mechanism connecting one of the tracers with the movable frame on which the work piece and the model are mounted, and width grading 45 mechanism connecting the other tracer with the other tool on the tool carriage.
11. A shaping machine comprising means for turning the work about a suitable axis, means for turning the model about the same axis, a movable frame on which both of said 50 means are mounted, two relatively movable tools movable in the direction of the axis of turning of the work piece, one designed for rough work and the other designed for 55 finishing work upon those portions of the work piece operated upon by the roughing tool, two relatively movable tracers movable in the direction of the axis of turning of the model, a connection between one of the 60 tracers and one of the tools for effecting relative movement between the tool, and a connection between the other of the tracers, and the movable frame on which the model and the work piece are supported for effecting 65 relative movement between the work piece and both tools.
12. A shaping machine comprising means for turning the work about a suitable axis, means for turning the model about the same axis, a movable frame on which both of said 70 means are mounted, two tools movable in the direction of the axis of turning of the work piece and mounted to turn about different axes both at angles other than right angles to the axis of turning of the work piece, one of said tools having a hollow portion in which a portion of the other of said tools operates and having also a movement 75 relatively to said other tool transversely of the axis of rotation of the work piece, and two tracers cooperating with a model on the model supporting means, movable in the direction of the axis of rotation of the model and also transversely of said axis of rotation, one of said tracers being connected with the frame on which the model and the work piece are mounted to effect the movement 80 of the work piece relatively to both tools, and the other of said tracers being connected with the hollow tool for effecting the movement of the latter relatively to the other tool.
13. A shaping machine comprising means for turning the work about a suitable axis, means for turning the model about a suitable axis, two tools movable in the direction of the axis of turning of the work piece, one of said tools being movable relatively to the other in a direction at an angle other than a right angle to the axis of turning of the work piece, and two tracers movable in the direction of the axis of turning of the model, one of said tracers being connected to a tool which is movable at an angle other than a right angle to the axis of turning of the work piece, and the other of said tracers controlling the relative positions between the work piece and both of the tools. 95
14. A shaping machine comprising means for turning the work about a suitable axis, means for turning the model about a suitable axis, two tools for operating on a work piece on the work piece turning means, one of said tools being movable relatively to the other transversely of the axis of turning of the work piece, two tracers, one of which controls the relative position between the two tools and the work piece, and a connection between the other tracer and the tool which is movable transversely of the axis of turning of the work piece. 100
15. A shaping machine comprising means for turning the work about a suitable axis, means for turning the model about a suitable axis, a movable frame on which both of said turning means are mounted, two tools movable in the direction of the axis of rotation of said work piece one of which is designed 105
- 110
- 115
- 120
- 125

for roughening work and the other designed for finishing, the surface traversed by the roughing tool, one of said tools being movable relatively to the other transversely of the 5 axis of rotation, two tracers, one of which is connected with the frame on which the work supporting means and the model supporting means are mounted for effecting the relative movement between the work piece and 10 the tools, a width grading mechanism connecting the other tracer and the tool which is movable transversely of the axis of rotation of the work piece, and a length grading mechanism connecting the two tools and the two 15 tracers.

16. A shaping machine comprising means 20 for turning the work about a suitable axis, means for turning the model about a suitable axis, a frame on which said work piece turning means and model turning means are mounted, a tool carriage, a tracer carriage, a length grading means connecting the tool carriage with the tracer carriage, means moving said carriages in the direction of the axis 25 of rotation of the work piece and the model, two relatively movable tools mounted on the tool carriage, two relatively movable tracers mounted on the tracer carriage, width grading mechanism connecting one of the tracers 30 with the frame on which the work piece and the model are mounted, and a width grading mechanism connecting the other tracer and the other tool and embodying a slide on which said tracer is mounted, a second slide 35 having a connection with the said tool which permits the length grading adjustment, a grading arm pivotally connected with the last mentioned slide and having a sliding fulcrum on the tracer carriage, and a link pivotally 40 connected to the slide on which the tracer is mounted and adjustable on the grading arm in the direction of the length of said arm and on opposite sides of the pivotal connection of the latter with the tool.

45 17. A shaping machine comprising means for turning the work about a suitable axis, means for turning the model about the same axis, a frame on which both of said means are mounted, a tool carriage and a tracer carriage adjustable in the direction of the axis of turning of the work piece and the model, length grading means connecting said two carriages, two tools mounted on said tool carriage, one of said tools having an adjustment 50 relatively to the other transversely of the axis of rotation of the work piece, two tracers mounted on the tracer carriage, one of said tracers having a connection with the frame on which the model and the work piece are 55 supported, a slide on which the other of said tracers is mounted, a second slide on which the first named slide is mounted to operate, said second slide being adjustable on the tracer carriage in the direction parallel with 60

the transversely adjustable tool on the tool 65 carriage, and a connection between said last mentioned slide and the said last mentioned tool permitting the length grading adjustment between the tracer and the tool carriage. 70

18. In combination with a machine for turning irregular forms, a cutter instrument inclined with and toward the line of feed and toward the work, and a second cutter instrument simultaneously engaging the same piece 75 of work in inclined relation opposite that of the first mentioned cutter instrument, one of said instruments serving as a roughing cutter and the other as a finishing cutter and operative over the same work area, one of said 80 cutter instruments being hollow and the other projected within it so that their cutting planes intersect permitting their respective points of contact with the work to approach each other closely and driving means for said 85 cutters.

19. A machine for turning irregular objects comprising rotating pattern and work supports, a traveling cutter head moving in a 90 fixed path of travel parallel with the axis of the work and arranged with its axis inclined to the axis of the work and at an acute angle with the line of travel of the cutter head, and a second cutter head traveling in unison with the first mentioned cutter head, and simultaneously movable transversely to the line of travel of the first cutter and to the axis of the work whereby the relations between the respective cutters to the work may be differentiated, said last mentioned cutter being 95 arranged, in an oppositely inclined relation with the axis of the work and line of travel, said cutter heads serving as roughing and finishing cutters operative over the same 100 work area. 105

20. A machine for turning irregular objects having rotating pattern and work supports including independent revoluble roughing and finishing cutter heads simultaneously 110 engaging the same piece of work and operative over the same work area, the work and cutter heads being relatively movable in a direction of travel substantially parallel with the axis of the work and control mechanism therefor and between which cutters and their 115 control mechanism and the work there is a proportionate shift transversely to the axis of the work in which the relation of the respective cutters and the work is variable to a different degree whereby the relation of the 120 respective cutters and work may be differentiated, the axes of the roughing and finishing cutter heads being angularly arranged in relation with each other and with the axis of the work and direction of relative travel. 125

21. A machine for turning irregular objects having rotating pattern and work supports, including independent revoluble rough-

ing and finishing cutter heads simultaneously engaging the same piece of work and operative over the same work area, the work and cutter heads being relatively movable in the 5 direction of travel substantially parallel with the axis of the work, the cutter heads being relatively adjustable transversely of said direction of travel during such traveling movement.

10 22. A machine for turning irregular forms having rotating work and pattern supports, including independent revolute roughing and finishing cutter heads simultaneously engaging the same piece of work and operable 15 over the same work area, said cutter heads rotating in intersecting planes, means for automatically adjusting one of said cutters to and from the work, independent of the other cutter, by the cooperation of a pattern carried 20 by said pattern support, and means for moving both cutters in unison in relation with the work.

23. A machine for turning irregular forms having rotating work and pattern supports, 25 including independent revolute roughing and finishing cutter heads, simultaneously engaging the same piece of work, and operable over the same work area, and an independent tracer member for each of the cutter heads.

30 24. A machine for turning irregular forms having rotating work and pattern supports, including, independent revolute roughing and finishing cutter heads simultaneously engaging the same piece of work and operable 35 over the same work area, said cutter heads being revolute in intersecting planes of rotation, and relatively adjustable under automatic control of a pattern.

25. A machine for turning irregular forms 40 having rotating work and pattern supports, including independent revolute roughing and finishing cutter heads simultaneously engaging the same piece of work and operable over the same work area, and means for independently controlling the operation of the 45 respective cutter heads, by a single pattern, whereby the respective cutter heads are movable relative to the work independently of each other.

50 26. A machine for turning irregular forms having rotating work and pattern supports, including independent revolute roughing and finishing cutter heads simultaneously engaging the same piece of work and operable 55 over the same work area, said cutter heads being angularly disposed and relatively adjustable in relation one with the other, said cutter heads being so constructed and arranged that one cutter may be projected across the plane 60 of rotation of the other.

27. A machine for turning irregular forms having rotating work and pattern supports, including independently adjustable revolute roughing and finishing cutter heads simultaneously 65 engaging the same piece of work

and operable over the same work area, the axes of rotation of the cutter heads being inclined one to the other and means for relatively adjusting the cutter heads automatically.

70 28. A machine for turning irregular forms having rotating work and pattern supports, including independent revolute roughing and finishing cutter heads simultaneously engaging the same piece of work and operable 75 over the same work area, the axes of rotation of the cutter heads being inclined one to the other, means for independently controlling the relative approach and recession of the cutters in relation with the work, and means 80 for effecting progression of the cutters substantially in unison in relation with the work.

29. In a machine for turning irregular shapes, having revolute work and pattern supports, including a revolute cutter head 85 in relation with which the work is laterally adjustable, said cutter head being movable in substantially parallel relation with the axis of the work, and a second cutter head operating over the same area traversed by the first 90 cutter movable in unison with the lateral movement of the work, but to different extent and movable relative to the work in unison with the travel of the first cutter said cutters being arranged with intersecting circles of 95 operation.

30. In a machine for turning irregular shapes having revolute work and pattern supports, including, two independent revolute cutter heads, the work and cutter heads 100 being movable one in relation with the other, in a direction of travel substantially parallel with the axis of the work, the work and one of the cutters being relatively movable one in relation with the other transversely to such 105 axial direction of relative travel, the work and other cutter being movable in unison transversely to said axial direction of relative travel, but to different extent.

31. In a machine for turning irregular 110 shapes, a revolute work support mounted for movement transversely of its axis of rotation, a roughing cutter and a finishing cutter, the work and cutters being relatively movable in a direction of travel substantially parallel 115 with said axis of rotation, one of the cutters being capable of movement transversely to said path of travel in unison with the transverse movement of the work, and means for governing the approach and recession movements of the work and respective cutters during their relative movement parallel with the axis of the work.

32. In a machine for turning irregular 120 forms, means for revolutely mounting the work and a pattern, two cutters simultaneously engageable with the same piece of work and operative over the same work area, said cutters being relatively adjustable in relation 125 with each other, and simultaneously relative-

- ly adjustable in relation with the work, and means controlled from the pattern for simultaneously varying the relation of the work with both the cutters to different extent.
- 5 33. In a machine for turning irregular forms, means for revolvably mounting the work for movement transversely of its axis of rotation, a cutter movable longitudinally of the work in relation with which the work is 70
10 movable by said transverse motion, a pattern engaging means controlling the approach of the work toward such cutter, a cutter member also mounted for movement transversely of the axis of rotation of the work in unison with 75
15 the movement of the work, and pattern engaging means for governing the relative extent of unison movement of the work and cutter whereby the relation of the work and cutter will be varied during such transverse
20 movement, said cutters being operable over the same area of the work, and means for effecting relative travel of the work and cutters in a direction substantially parallel with the axis of rotation of the work.
- 25 34. A machine for turning irregular forms having work and pattern rotating means, including a revolvable roughing cutter and revolvable finishing cutter, simultaneously engaging the same piece of work in juxtaposed 80
30 paths of operation, said cutters being mounted to rotate in intersecting circles of rotation and automatic means to relatively move said cutter heads to vary the over-lapping relation of their circles of rotation.
- 35 35. A machine for turning irregular forms having work and pattern rotating means, including a revolvable roughing cutter and a revolvable finishing cutter simultaneously engaging the same piece of work in juxtaposed 85
40 path of operation, one of said cutters being hollow and the other cutter being partially projected within the hollow cutter, said cutters being relatively movable to vary such overlapping relation wherein the cutting 90
45 plane of one cutter angularly intersects the cutting plane of the other cutter, permitting their respective points of contact with the work to approach each other closely, automatic control means and driving means for 100
50 said cutters.
- 55 36. In a machine for turning irregular shapes, the combination with work and pattern rotating means of revolvable roughing cutter and a revolvable finishing cutter mounted for simultaneous engagement with the 105
60 same piece of work in closely associated paths of operation, means for relatively moving the cutters and work in a direction substantially parallel with the axis of rotation of the work, means for relatively adjusting the 110
65 cutters and work in a direction transversely in relation with the axis of rotation of the work, the relative variation of the work and respective cutters being to different extent 115
70 during such transverse adjustment.
37. In a machine for turning irregular shapes the combination with work and pattern rotating means, of a revolvable, roughing cutter and a revolvable finishing cutter mounted for simultaneous engagement with the same piece of work in closely associated paths of operation, means for relatively moving the cutters and work in a direction substantially parallel with the axis of rotation of the work, means for moving both the work and one of the cutters transversely to the axis of rotation of the work independent of the remaining cutter. 75
80
38. In a machine for turning irregular shapes, the combination with work and pattern rotating means, of a revolvable roughing cutter and a revolvable finishing cutter mounted for simultaneous engagement with the same piece of work in closely associated paths of operation, means for relatively moving the cutters and work in a direction substantially parallel with the axis of rotation of the work, and means for differentially moving said work and cutters transversely to the axis of rotation of the work simultaneously with their movement parallel thereto, substantially as specified. 85
90
39. In a machine for turning irregular shapes, a revolvable work support capable of movement to and fro transversely to the axis of rotation, a revolvable cutter movable in a fixed path of travel substantially parallel with the axis of the work toward and from which the work is movable by the to and fro movement of the work support and a second revolvable cutter mounted for movement transversely to the axis of rotation of the work, a tracer member controlling the transverse movement of the work supports relative to said cutters and an independent tracer member controlling the transverse movement of the second cutter and following the to and fro movement of the work support to effect a differential relation between the respective cutters and between said cutters and the work, and means for also moving the second cutter longitudinally of the work independent of its transverse movement. 95
100
40. In a machine for turning irregular shapes a revolvable work support movable to and fro transversely to its axis of rotation, a cutter movable in a fixed path of travel parallel with the axis of the work, and a second cutter member mounted for to and fro movement transversely to the axis of rotation of the work and also movable longitudinally of the work, and a guide pattern common to both the cutters and independent tracer members simultaneously engaging the guide pattern and capable of relative movement one to the other determining the relative range of to and fro transverse movements of one cutter in relation with the other and the work relative to both cutters. 105
110
41. In a machine for turning irregular 115
120
125
130

- shapes, a revoluble work support movable to and fro transversely to its axis of rotation, a cutter movable in a fixed path of travel substantially parallel to the axis of the work, 5 and a second cutter member mounted for to and fro movement transversely to the axis of rotation of the work and also movable longitudinally of the work, independently operable tracer members, one of which controls the transverse movement of the work support to and from the first cutter, the other of which controls the to and fro movement of the second cutter relative to the movable work support simultaneously with the movement 10 of the latter and a guide pattern common to both tracer members, and means for differentially moving said work and cutter through their to and fro transverse range of movement.
- 15 42. In a machine for turning irregular shapes, a revoluble work support movable to and fro transversely to its axis of rotation, a relatively fixed cutter member and a cutter member mounted for to and fro movement transversely to the axis of rotation of the work both cutter members being movable longitudinally of the work and means for simultaneously moving the work and second cutter toward and from each other through 20 predetermined degrees of movement as the cutter progresses longitudinally of the work, including a tracer member controlling the movement of the work and a second independently movable tracer member controlling the movement of said second cutter and a guide pattern common to both tracer members.
- 25 43. In a machine for turning irregular shapes, a revoluble work support movable to and fro transversely to its axis of rotation a hollow cutter member movable in a fixed path substantially parallel with the axis of the work and a hollow cutter member projecting partially within the hollow cutter 30 so that their cutting planes intersect and permitting their respective points of contact with the work to approach each other, said hollow cutter being mounted for to and fro movement transversely to the axis of rotation of the work and also movable longitudinally of the work, independent tracer members, one of which is movable relative to the other controlling the to and fro movement of the work support 35 and the to and fro movement of the hollow cutter relative to the movable work and a guide pattern common to both of the tracer members.
44. In a wood working machine and the like, a work support, and a pair of revoluble cutters associated therewith, for simultaneous engagement with the work, one of the cutters being hollow, the second cutter projecting within the hollow of the other cutter, substantially as specified. 45. In a wood working machine and the like, the combination with a work support of a pair of independently revoluble cutters for simultaneous engagement with the work rotating in angularly disposed planes, one of the cutters being hollow, and the other cutter intersecting the plane of rotation of the hollow cutter, substantially as specified. 50 46. In combination in a machine for turning irregular forms, two cutter instruments operating over the same area of the work, control mechanism therefor and between which cutters and their control mechanism and the work there is a proportionate shifting to control the size of reproduction in which one cutter is fixed and the cooperating mechanism and work shift laterally thereto while the other cutter shifts with reference to the work and control, whereby the relations between the respective cutters to the work may be differentiated. 55 47. In a machine for turning irregular objects, the combination with rotating pattern and work supports, of a traveling rotating cutter head arranged with its axis oblique to the axis of the work holder and inclined toward the work and with the line of feed, and a second cutter head also arranged with its axis oblique to the axis of the work and inclined toward the work on a direction contrary to the line of feed, one of said cutter heads being hollow and the other projected within it so that their cutting planes intersect permitting their respective points of contact with the work to approach each other closely, control mechanism therefor and between which cutters and their control mechanism and the work there is a proportionate shift to control the size of reproduction one of said cutters being confined to a fixed path of travel and the cooperating control mechanism and work laterally shift relative thereto while the other cutter shifts with reference to the work and control whereby the relation of the respective cutters to the work may be differentiated. 60 65 70 75 80 85 90 95 100 105 110

STANLEY E. BOYNTON.
